UNITED STATES PATENT OFFICE.

SETH ROGERS, OF BALLSTON SPA, NEW YORK.

CURRY-COMB.

SPECIFICATION forming part of Letters Patent No. 444,185, dated January 6, 1891.

Application filed May 7, 1890. Serial No. 350,930. (No model.)

To all whom it may concern:

Be it known that I, SETH ROGERS, a citizen of the United States, residing at Ballston Spa, in the county of Saratoga and State of New York, have invented a new and useful Improvement in Curry-Combs, of which the following is a specification.

My invention relates to improvements in curry-combs, in which an endless spiral wire encircles an endless wire hoop for the purpose of producing an elastic and non-irritating curry-comb for cleaning horses, also one that can be manufactured cheaply. I attain these objects by the following mechanism, illustrated in the accompanying drawing, in which the figure is a full-size view of the curry-comb as constructed.

Similar letters refer to similar parts throughout.

a is an endless wire hoop made from suitable strength wire to give firmness.

b is an endless spiral wire encircling the wire hoop *a*.

What I claim, and desire to secure by Letters Patent, is—

A curry-comb constructed from a spiral wire *b*, encircling a wire hoop *a*, substantially as shown, and for the purpose specified.

SETH ROGERS.
